TELEGRAPH TAPE REPERFORATOR

James A. Spencer, Teaneck, N. J., assignor to
Radio Corporation of America, a corporation of
Delaware

Application July 22, 1942, Serial No. 451,878

8 Claims. (Cl. 164—114)

1

This invention relates to improvements in telegraph tape reperforators and has particularly to do with a device of this character which is capable of automatic operation for duplicating in a plurality of tapes the code signals which were previously perforated in a master tape. My invention has particular utility in the preparation of duplicate tapes, one of which is intended to be utilized at the place where it is prepared, and the other of which is intended to be transported physically in a sealed package to the intended receiving station in time to be used for deciphering cryptographic messages. The invention is not, however, limited to such use.

In cryptographic telegraphy it is necessary to utilize identical tapes for ciphering at the transmitting station and for deciphering at the receiving station. Heretofore such tapes have been prepared individually by keyboard perforators.

Cryptographic tapes are used in conjunction with message tapes for interchanging the marking and spacing elements of code signals so that they shall be rendered unintelligible if the signals themselves are intercepted by an unauthorized person. In an application Serial No. 444,658, which was filed May 27, 1942, jointly by Loyd A. Briggs and myself, a system is disclosed wherein an enciphering tape is used simultaneously with a message tape at a transmitting station for characterizing the marking and spacing elements of code signals. That system also discloses how a replica of the enciphering tape may be used at the receiving station as a deciphering tape. When deciphering is to be accomplished, the received signals are utilized jointly with impulses locally derived from a deciphering tape sensing device so that all sense reversals which were produced at the transmitter by the cryptographic tape are compensated and the original code signals of the message tape are restored. It will, therefore, be apparent that such restoration could not be obtained at the receiving station unless the perforated tapes used at each end of the circuit are identical.

Accordingly, it is an object of my invention to provide a telegraph tape reperforator which is suited to the requirements for automatically reading the perforations in a given master tape and newly perforating a plurality of tapes which shall be exact duplicates of the master tape.

It is another object of my invention to provide a multiple reperforator which includes the necessary mechanism for sensing the perforations in a master tape and for translating the sensing

2 operation into a reperforating operation applied to a plurality of blank tapes.

Among the advantageous features of my invention is the facility with which a cryptographic or other tape of any desired length may be prepared in duplicate by using sequentially a number of shorter lengths of master tape. It is an object of my invention to provide this facility, so that duplicate tapes of any desired length may be made available for cryptographic signalling without danger of interruption of cryptographic message transmission by breakage of spliced pieces of tape.

Other objects of my invention, as well as advantages thereof, will be brought out in the description to follow. This description is accompanied by a drawing, the sole figure of which shows in an elevation view the essential parts of a multiple tape reperforator constituting a preferred embodiment of my invention.

20 While there are numerous types of telegraph tape perforators which have been in commercial use for a long time, I have found that one known as the Wheatstone perforator may readily be modified and supplemented by new mechanism in such manner as to carry out the objects of my invention. The invention though not limited to the use of a modified Wheatstone perforator is best illustrated in combination with such a device. To those skilled in the art, it is well known that 25 a Wheatstone perforator may be manually operated for spacing the tape as the code perforations are applied. A row of feed holes is also perforated simultaneously with the rows of holes representing the code signals. If the tape is intended for use in a Morse code signal transmitter or in a cable code transmitter, then only two rows of code perforations are applied longitudinally of the tape. When, however, the tape is to be used for five-unit or seven-unit printer 30 code signals, the perforations are generally arranged transversely of the tape and on both sides of the sprocket feed holes. In the embodiment herein illustrated, the principles of my invention are sufficiently exemplified by its application 35 to a Morse signal perforator. Such changes as will be necessary for adapting the invention to a printer code perforator involves merely the addition of more punches and punch hammers, as will be apparent to those skilled in the art.

40 In order to sense the perforations in a master tape, I preferably feed such a tape 45 step-by-step through a gate G by means of a sprocket wheel 4. The sprocket teeth of this wheel mesh with the center holes in the tape. The tape is held in place for the sensing operation by means

of a latch 1. In accordance with conventional tape transmitter design, the latch 1 can be lifted away from the gate G for insertion of the tape at the outset.

The seekers 2 are constituted as prongs on a plurality of levers L, which levers are pivoted at 21. The seeker prongs 2 are urged upwardly by means of springs 15. A shaft 22 is constantly driven by a motor (not shown) and carries a cam 8 for engagement with follower rollers 23 and 24, in order to actuate the lever arms 25 and 26 respectively.

Lever arm 25 is pivoted at 13 and carries a flexible bail 6 for engagement with each of the detents 27, the latter being integral with respective ones of levers L. By means of a screw 11 threaded into the lever 25 and held in place by a lock nut 28, the extent of movement of the lever L is adjustably controlled.

At the upper end of the lever 25 is pivoted a pawl member 5 arranged to cooperate with a ratchet wheel R on the shaft of the feed sprocket. The pawl is held in engagement with the ratchet wheel by means of a spring 16.

It is apparent that when the crown of the cam 8 moves the bail 6 to the right, the seeker pins 2 are withdrawn from perforations in the tape and immediately thereafter the tape is fed from right to left by the counter-clockwise rotation of the sprocket wheel 4, this rotation being provided by a retractive movement of the pawl 5.

When the bail 6 returns to its normal position, the seekers 2 are caused to rise under the influence of the springs 15. If one or another seeker passes through a perforation in the tape 18, then a lever 3 is lifted sufficiently to place its projection 34 in line with a hammer head 35 on a punch bail 7. This punch bail is mounted on the lever arm 26 by means of a screw 29. The lever arm 26 is pivoted at 12. The upper end of the bail 7 is adjustably spaced away from the lever 26 by means of a screw 17 threaded into lever 26 and secured thereto by means of a lock nut 30.

The levers 3 are arranged to coact with punches 31, the latter being held in place in a punch block 10 and suitably aligned with a gate, or die member 32 through an opening in which one or more blank tapes may be fed.

The mechanism necessary to feed the blank tapes through gate 32 has not been shown because it is of well-known construction, and forms no part of the instant invention. It will be understood, however, that such feeding mechanism may comprise a sprocket wheel similar to the sprocket wheel 4, and that it may be actuated in step with the sprocket wheel 4 simply by providing a reciprocating pawl to be driven by the same motor as that which drives the cam shaft 22.

In addition to the punches 31 which are required for punching the code perforations in the new tapes in accordance with perforations sensed by the seekers 2 in the master tape 18, I provide a center-hole punch 33 which is actuatable by a plunger bar 39, the latter being slideable in ways formed in a guide block 40. The manipulation of the cam 20 may be facilitated by the use of a handle 9 by which the cam may be rotated through an angle of substantially 90° on its pivot center. There is no need to lift and lower the right hand end of the plunger bar 39 since it must be actuated at every stroke of the bail 1. Hence, the lifting lugs 3a are provided only for the two lever bars 3. Furthermore, the

plunger bar 39 requires no spring 19, since its right hand end is always held at a suitable level to be struck by the projection 35 on bail 7.

When one (or both) of the seekers 2 is opposed by an unpunched portion of the master tape 18, then the lever L fails to rise appreciably. The projection 34 does not rise to the level of the hammer head 35 on the end of bail 7. In such case, therefore, no operation of the corresponding punch 31 will take place.

As the cam 8 continues to rotate, bail 7 returns to its normal position under the influence of a spring 14. The punches 31 and 33 are then permitted to be withdrawn from the tape or tapes passing through the die block 32. This withdrawal is effected by means of springs 36 operating upon a movable plate 37 and against shoulders 38 on the punches 31 and 33.

In order to hold the levers 3 out of the path 20 of the hammer head 35 on the bail 7 while inserting tapes under the latch 1, it is preferable to utilize a cam 20 which can be rotated through an arc of 90° by manual operation. This operation locks down the levers 3 until such time 25 as it is desired to start the punching operation.

In view of the foregoing description, the operation of my invention, simple as it is, will be well understood by those skilled in the art.

It will be also understood that my invention 30 is capable of being carried out by means of other constructions than those herein shown and described. The claims, therefore, are to be construed as though not limited to the exact details of mechanism herein shown by way of 35 illustration.

I claim:

1. A telegraph tape reperforator comprising a plurality of tape-perforation seeker members arranged in alignment with rows of code perforations in a master tape to be fed past a sensing position, mechanism actuated by a single rotary cam for causing said seeker members to perform a sensing operation, a tape perforator having punches corresponding to said seeker members, 45 punch selectors individual to said punches, at least two of said selectors being selectable by said mechanism in accordance with said code perforations, and a bail reciprocally operable by said cam upon each revolution thereof to communicate power through selected ones of said selectors to their respective punches, thereby to reperforate new tape in accordance with said master tape.

2. Tape perforating apparatus comprising in combination, a controlling device having seeker pins aligned with rows of code perforations to be sensed in a master tape after each step of tape feed, a single rotary cam, means including a pawl pivoted on a lever arm and reciprocally actuated by said cam in cooperation with a spring, whereby said master tape is fed step-by-step past a sensing position, lever means actuated by said cam for periodically withdrawing said seeker pins from the plane of said master tape, a tape perforator assembly having code punches corresponding to said seeker pins and a feed-hole punch, punch selectors individual to each of said punches, a bail actuatable by said cam, means actuated by said seeker pins for providing selective control of the selectors associated with said code punches, and means including a bail reciprocally actuated by said cam in cooperation with said spring for applying power to selected ones of said selectors thereby to perforate replica tapes 70 in accordance with said master tape.

3. In a telegraph tape reperforator, a plurality of reciprocable seeker pins adapted to sense the presence or absence of code perforations at different positions in a master tape, a punch and die mechanism having a blank tape holder, one continuously rotatable cam operable in association with a reciprocable punch bail for causing said mechanism to work upon strips of tape in said holder, a single cam follower means actuatable by said cam for feeding said master tape stepwise and for reciprocating said seeker pins, and another single cam follower means actuatable by said cam and operable through said punch bail for actuating selected punches of said mechanism, the selection whereof is effected by the sensing operation of said seeker pins.

4. A telegraph tape perforator comprising a punch and die assembly having a feed-hole punch and a plurality of code character punches, a punch selector individual to each of said punches, a continuously rotatable cam, two reciprocating levers, each having an idler roller journaled thereon, said levers being pivotally mounted for sequential actuation by a single hump on the periphery of said cam, resilient means for maintaining contact between said idler rollers and the periphery of said cam, a master tape the code character perforations in which are to be copied in perforating new tape, a master tape sensing device comprising reciprocable seeker pins and a tape feeding mechanism, said sensing device being actuatable by one of said reciprocating levers, means for causing each seeker pin, when it finds a code perforation in the master tape, to select a corresponding one of said punch selectors, and a punch hammer operable by the other of said reciprocating levers, in cooperation with a non-selectable one of said punch selectors to perforate said new tape with a continuous row of feed holes, also to perforate code holes by cooperation with selected ones of said punch selectors.

5. A telegraph tape perforator comprising a

punch-and-die assembly having a feed-hole punch and a plurality of code character punches, a reciprocable lever system having two levers disposed in diametric opposition to a continuously rotatable cam, said levers being alternately movable by said cam during an operating cycle, a master tape having code character perforations which are to be copied in perforating new tape, means operable by one of said levers for sensing the code perforations in said master tape, and a selectively operable device under joint control of said sensing means and of the other one of said levers for causing said new tape to be perforated by said punch-and-die assembly in accordance with said master tape.

6. A perforator in accordance with claim 5, and including a non-selectable punch striker for communicating the motion of the "other" of said levers to said feed-hole punch.

7. A perforator in accordance with claim 5, and including a plurality of punch strikers selectable by said sensing means for communicating the motion of the "other" of said levers to said code character punches.

8. A telegraph tape reperforator comprising a master tape feeding device operable step-by-step to bring successive transverse rows of code perforations into a sensing position, sensing means operable at each step of said feeding device to detect the code combination punched in said tape, a plurality of punches arranged to perforate a replica tape, a punch bail reciprocable at the cadence of the step-by-step operation of said feeding device, means under control of said sensing means for causing said bail to apply power to selected punches, and a driving mechanism for actuating the tape feeding device, the sensing means, and the bail, said mechanism including a rotary cam against the periphery of which two diametrically opposed cam followers are pressed.

JAMES A. SPENCER.
